Primary Examiner — George D. Kirschbaum*Assistant Examiner* — Joseph J Kukella(74) *Attorney, Agent, or Firm* — Shaun J. Fox**CLAIM**

The ornamental design for a tire, as shown and described.

DESCRIPTION

FIG. 1 is a side perspective view of a tire showing our new design;

FIG. 2 is a front elevational view thereof;

FIG. 3 is a side elevational view of the left side thereof; and,

FIG. 4 is a side elevational view of the right side thereof;

FIG. 5 is an enlarged fragmentary view thereof. In the drawings, the broken lines depict environmental subject matter only and form no part of the claimed design.

1 Claim, 5 Drawing Sheets(56)
